UNITED STATES PATENT OFFICE.

SAXTON J. MORGAN, OF ALBANY, WISCONSIN.

GEARING FOR DRILL-PRESSES.

No. 801,885.

Specification of Letters Patent.

Patented Oct. 20, 1908.

Application filed December 20, 1907. Serial No. 403,633.

To all whom it may concern:

Be it known that I, SAXTON J. MORGAN, a citizen of the United States, residing at Albany, in the county of Greene and State of Wisconsin, have invented a new and useful Gearing for Drill-Presses, of which the following is a specification.

This invention relates to gearing for drill presses, and has for its principal object to provide improved means for driving the drill spindle and changing its speed of rotation in accordance with the quality of the material being operated upon, the speed changing mechanism being so arranged as to permit adjustment of the speed without stopping the machine.

A further object of the invention is to provide improved form of transmission mechanism which may be readily adjusted for the purpose of stopping and starting the rotation of the drill spindle, and which, when moved to idle position, will leave the drill spindle entirely free, so that the chuck may be turned into proper position for using the wrench to tighten or release the drill.

A still further object of the invention is to provide a friction drive of this class in which the driving elements may be held together under any desired degree of pressure. With these and other objects in view, as will more fully hereinafter appear, the invention consists in certain novel features of construction and arrangement of parts, hereinafter fully described and claimed.

In the accompanying drawings.—Figure 1 is a side elevation of a drill press constructed in accordance with the invention. Fig. 2 is a front elevation of the same. Fig. 3 is a transverse sectional view of a portion of the driving mechanism.

Similar numerals of reference are employed to indicate corresponding parts throughout the several figures of the drawings.

The standard 10 is provided with a bracket 11 for the support of a drill platform 12 of ordinary construction, and at the upper portion of the standard are outwardly extending arms 15 and 16, that are provided with bearings for the support of the drill spindle 17. The upper end of the standard 10 is extended on a curved line, and is provided with two arms 18 and 19 forming bearings for a shaft 20 on which is secured a driving pulley 21 to which motion may be transmitted from a line shaft in the ordinary manner.

The two spaced arms 15 and 19 of the frame are connected to each other and reinforced by a connecting bar 22 that is provided with a strengthening rib 23 as indicated in Fig. 60 3, and the inner faces of the arms 15 and 19 and the bar 22 are arranged on curved lines that form a practically complete circle.

To the upper portion of the standard 10 is secured a block 24 that is provided with a groove for the reception of a rib 25 that projects from the lower face of an adjustable block 26, the rib and groove being preferably dove-tailed in cross section in order to prevent separation of the two blocks, while the meeting faces of the blocks are arranged on a line substantially radial of the circle previously referred to, and are disposed at an angle of approximately 45° to the vertical plane of the standard 10.

To the lower end of the block 26 is swiveled a screw 27 that is arranged in a threaded opening formed in the upper portion of the standard, and said screw carries a hand wheel 28 which may be turned for the purpose of moving the block 26 in the direction of its length.

To the upper portion of the block 26 is pivoted a yoke 29 and from this yoke extends a shouldered pivot pin 30 on which is mounted a hemi-spherical friction gear 31 which is free to rotate on the pin 30, and which is adjusted by turning the handled screw 27. With the surface of this friction gear 31 engages a pair of friction disks 32 and 33, the disk 32 being secured to the drive shaft 20, and the disk 33 being connected to the drill spindle 17 in the usual manner, so that the driving disk 32 will impart movement to the hemi-spherical member, and the latter will drive the spindle disk 33.

To the yoke 29 is secured a U-shaped arm 34, and to the outer end of this arm is secured a spring lever 35 carrying a handle 36 at its upper free end. The upper portion 100 of the lever 35 lies against the outer face of the curved bar 22, and is held there against by the action of the spring. To the upper portion of the spring proper, and just below the handle, is secured a U-shaped arm 38, 105 one of the vertical members 39 of this arm being arranged to enter a series of locking notches 40 that serve to hold the lever in any position to which it may be adjusted, while the inner arm 40 serves by engagement with 110 the rib 23 to limit the outward movement of the lever as it is moved to disengage from

the notches and thus prevent such excess movement as would tend to strain the lever and destroy the effectiveness of the spring.

By turning the lever, the position of the 5 hemi-spherical member 31 may be adjusted, so as to alter the speed at which the drill spindle is revolved.

In the position shown in Fig. 1, the lever is in the mid position, the two disks 32 and 10 33 being in contact with the hemi-sphere 31 at precisely the same distance from the center of the driving surface of said sphere, so that the speed of the spindle is equal to the speed of the shaft 20. If the lever is moved 15 down to the lowermost of the notches 40, the hemi-sphere will be so adjusted that the driving disk 32 will be in engagement with the largest diameter of the driving surface of the sphere, while the driven disk will be 20 in engagement with its smallest surface and the drill spindle will, therefore, be rotated at a speed much lower than that of the driving shaft 20. If the lever is moved in the opposite direction, or toward the highest of 25 the notches 40, the driving disk 32 will engage the smallest portion of the friction surface of the hemi-sphere, and the spindle disk will engage the largest diameter thereof, so that the spindle will be rotated at a speed 30 much greater than that of the driving shaft 20.

The drill spindle may be rotated at any speed necessary for ordinary work, and in machines as now constructed, it is found that 35 with a speed of seven hundred and ten revolutions per minute of the drive shaft, the spindle may be rotated as high as two thousand, six hundred and fifty revolutions per minute, or as low as one hundred and seventy-four revolutions per minute, or at any speed between these two.

In order that the drill press may be used to the best advantage by persons unfamiliar with the drill speeds best adapted for drilling 45 in different metals, the connecting bar 22 is provided with an indicating table 42. This table, as shown in Fig. 2, is divided into three columns paralleled with the row of notches 40, and at the bottom of each column 50 are designating marks, SS to indicate soft steel; CI, to designate cast iron, and B to designate brass. These columns are divided by cross lines into rows of spaces that are in alignment with the various notches 40 and 55 in the spaces thus formed are numerals designating drill diameters so that when a drill of particular size is used, say a drill of one-half inch in diameter, and the material is soft steel, the operator will move the lever 60 to the mark one-half in the SS column, but in drilling in cast iron, would move the lever to the mark one-half in the CI column, and so on, thus avoiding danger of spoiling the 65 drills and work while at the same time insuring the utmost speed of the work.

One of the principal advantages of the present construction is the ease with which the device may be thrown into and out of operation.

In order to stop the drive, it is merely 70 necessary to turn the handled screw 27 so as to draw the hemi-sphere 31 out of contact with the driving disk 32, and this, also, draws the hemisphere out of contact with the spindle disk 33, so that the drill spindle 75 as a whole is left free and may be readily turned by hand, so as to bring the chuck to a convenient position for the use of the wrench in tightening or loosening the drill. In a great many drill chucks, it is necessary 80 to turn the chuck to a certain position in order to release the drill, and in many drill presses it is necessary to turn not only the spindle, but all of the driving mechanism as well in order to swing the chuck around 85 into proper position for using the wrench, while in the present case the spindle is entirely free and may be turned by hand. The screw 27, moreover, permits adjustment of the frictional contact between the driving 90 members, and while this contact need be but light during high speeds, it is advisable to increase the pressure during the lower speeds, where the work is heavier.

I claim:—

1. In a variable friction gear, a driving and driven disk, an adjustable sliding support, a transmission friction member intermediate of said disks and connected to and mounted on said support by a rocking joint, 100 and means for adjusting said intermediate member to vary the points of contact between said member and the disks.

2. In a variable friction gear, a driving and a driven disk, a hemi-spherical intermediate friction member, a sliding support having a rocking joint on which said intermediate member is mounted, means for adjusting said sliding support, and means for adjusting the intermediate member in the 110 arc of a circle, and locking it in said adjusted position.

3. In combination, a frame having a pair of spaced arms, bearings carried by said arms, a pair of shafts journaled in the bearings and disposed at an angle to each other, friction disks carried by the shafts, an arched bar forming a connection between said arms and provided at one edge with a series of notches, an adjustable block carried by the 115 frame, a second block pivoted to the adjustable block, a hemi-spherical friction member revolvably mounted upon said second block, and frictionally engaging both disks, and a spring adjusting lever connected to the pivoted block and arranged to interlock with the notches to hold said block in adjusted position.

4. In combination, a frame having a pair of spaced arms, bearings carried thereby, a 120

pair of shafts journaled in said bearings and disposed at an angle to each other, an arched bar connecting said arms and provided with a strengthening rib, said bar having a series 5 of locking notches at one edge, a block supported by the frame, a screw for adjusting said block, a second block pivoted to the adjustable block, a hemi-spherical friction member revolvably mounted upon the second 10 block and frictionally engaging both disks, an arm extending from the second block, a handled spring secured to said arm and forming an adjusting lever and a U-shaped arm

carried by the lever and having a portion arranged to engage the notches of said arm 15 and bar, and an arm serving by engagement with the rib of said bar to limit outward movement of the lever.

In testimony that I claim the foregoing as my own, I have hereto affixed my signature 20 in the presence of two witnesses.

SAXTON J. MORGAN.
